(57) **CLAIM**

The ornamental design for a compact head-mounted display system, as shown and described.

DESCRIPTION

FIG. 1 is a first perspective view of the compact head-mounted display system showing my new design.

FIG. 2 is a second perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines are for environmental purposes only and form no part of the claimed design. The design shown is not to be limited to any particular size and may be scaled larger or smaller.

1 Claim, 8 Drawing Sheets
